WINDOW BAG

Filed June 30, 1930

UNITED STATES PATENT OFFICE

TRUE M. AVERY, OF GLENS FALLS, NEW YORK, ASSIGNOR TO UNION BAG & PAPER CORPORATION, OF HUDSON FALLS, NEW YORK, A CORPORATION OF NEW JERSEY

WINDOW BAG

Application filed June 30, 1930. Serial No. 464,967.

The present invention relates to improvements in bags adapted to contain or enclose articles or commodities of various kinds, it relating more particularly to bags of the kind having a window or open face covered by transparent material through which the contents of the bag will be visible.

One of the primary objects of the invention is to provide a bag of this kind having a strip 10 extending across the window near the mouth or open end of the bag and reinforcing the transparent material so as to prevent tearing thereof during filling or other handling of the bag, a tie or closure means being preferably associated with the reinforcing strip and serving as means for holding the mouth of the bag in closed condition.

Another object is to provide a bag of this kind which is composed of only two strips of material; that is, the strip of ordinary paper which forms the major portion of the bag, and the strip of transparent material which covers or closes the window therein, and which requires the use of only two seams.

25 To these and other ends, the invention consists in certain improvements which will be hereinafter described, the features of novelty being pointed out particularly in the claims at the end of this specification.

30 In the accompanying drawings:—

Fig. 1 is a perspective view of a window bag embodying the present invention, the bag shown in rear elevation and in open condition and having a portion broken away for 35 clearness in illustration;

Fig. 2 is an elevation of the upper end of the bag as viewed from the front, the bag mouth being in open condition;

40 Fig. 3 is a view similar to Fig. 2 showing the bag mouth in closed condition;

Fig. 4 is a view similar to Fig. 3 but showing the upper end of the bag rolled about the tie;

45 Fig. 5 is a top plan view of the closed bag showing the tie in fastened condition;

Fig. 6 is a perspective view of the upper end of the bag in closed condition and fastened by the tie;

50 Fig. 7 represents a transverse section

through the open bag, taken on the line 7—7 of Fig. 1;

Fig. 8 represents a fragmentary vertical section taken on the line 8—8 of Fig. 7;

Fig. 9 is a detail perspective view of the 55 reinforcing strip and tie before its application to the bag; and

Fig. 10 represents a transverse section taken on the line 10—10 of Fig. 9.

Similar parts are designated by the same 60 reference characters in the several figures.

The present invention is applicable to window bags of various types, it being shown for example, applied to a bag of the so called square bottom type.

In the present instance, the bag comprises a body portion 1 which is composed of ordinary flexible or foldable fiber paper such as that commonly used in the manufacture of paper bags, and a strip 2 composed of thin 70 flexible or foldable transparent sheet material such as "Cellophane" or any of the other well known thin transparent flexible sheet cellulose products obtained from viscose. The body portion 1 of the bag is approximately tubular in cross section, it having a wall 3 which forms the front of the bag, sides 4 which form the sides of the bag and which, in the case of a square bottom bag are pleated as shown so that the front of the bag 75 may collapse against the back of the bag, and portions 5 opposite to the wall 3 which are separated transversely, leaving a longitudinal gap in this wall of the tube which forms a window opening 6 in the back of the bag. 80

The strip of transparent material 2, which extends throughout the height of the bag, is pasted or otherwise secured to the inner sides of the portions 5 of the bag body so that it extends across and provides a transparent 85 covering for the window opening in the back of the bag. The strip of transparent material 2 is preferably somewhat narrower than the width of the back of the bag as shown in Fig. 7. The bottom of the bag is closed by 90 doubling or folding its lower end against the back of the bag, forming a flap 7 of the paper composing the body of the bag which flap is pasted to the portions 5 and the lower portion 95 of the transparent material 2 and thereby 100

provides a reinforcement for the transparent material covering the window opening at the bottom of the bag. In applying the invention to bags of the flat type, the pleats 5 are omitted, the front and back of the bag being united directly at the edges, as will be readily understood, and in applying the invention to bags of the so called automatic type, the bottom of the bag may be formed or folded as is common in bags of that type.

It will be understood that the bag, in each instance, will be composed of thin flexible material and can be opened, filled, closed and handled in a manner similar to ordinary paper bags. It will also be apparent that in each instance, the bag can be manufactured inexpensively on an ordinary bag making machine, the single strip of material 1 comprising the body of the bag being of less width than usual in making ordinary bags so that it will not form a complete tube, but will leave a gap between its longitudinal edges when formed into a tube, thereby leaving the window opening 6 extending longitudinally the full length of the bag tube, and the strip of transparent material 2 can be fed into position at the inner sides of the portions 5 along the longitudinal edges of the tube and secured in place by paste applied to the inner sides of the portions 5, the bottom of the bag being closed by the usual bottom folding mechanism, commonly employed in bag making machines.

A reinforcing strip 8, composed preferably of tough paper or other suitable flexible or foldable material is extended across the upper portion of the back of the bag adjacent to the mouth thereof, this reinforcing strip being pasted to the portions 5 and to the intervening portion of the transparent material 2, it providing a strong reinforcement which will resist or prevent tearing of the upper edge of the transparent material 2 at or near the bag mouth during filling or other handling of the bag. This reinforcing strip preferably has associated with it a tie for holding the bag mouth in closed condition. As shown, the tie comprises a narrow strip 9 of thin foldable metal such for example as tin about which the upper edge of the reinforcing strip is rolled so as to enclose it, as will be clear from Figs. 9 and 10. Before the bag is used, the portion of the reinforcing strip containing the tie would project above the upper edge of the mouth of the bag as shown in Figs. 1 and 2, but after the bag has been filled and the front and back of the bag mouth have been brought together as shown in Fig. 3, the bag mouth is rolled down on the front of the bag about the strip into the form shown in Fig. 4 whereby the bag mouth is completely closed, and the extremities 9a of the tie are then bent back and against the back of the bag to clench them as shown in Figs. 5 and 6, these ends of the

tie, although pliable, possessing sufficient strength or stiffness to remain in bent or clenched form and thereby hold the bag mouth in closed condition. Opening of the bag may be accomplished readily by bending back or unclenching the ends of the tie and then unrolling the bag mouth.

By forming the bag of the approximately tubular body portion 1 of ordinary paper, having the window opening in the back of the bag between the portions 5, and covering the window opening by the strip 2 of transparent material, the bag may be made from only two strips of material requiring seams only at the points between the longitudinal margins of the transparent strip and the longitudinal edges of the body portion of the bag, and enabling the strip of transparent material to be fed to the upper side of the usual former and the paper strip for the body of the bag to be fed to the under side thereof, thus facilitating the manufacture of the bags on ordinary bag making machines and reducing the cost thereof because of the relatively small amount of the transparent material required, and moreover, leaving the front 3 of the bag seamless so that it provides a surface on which advertising or other matter may be printed.

The reinforcing strip spanning the window opening and the transparent material covering it and pasted to the transparent material and the longitudinal portions of the paper body portion of the bag at the margins of the window opening effectually prevents tearing or breaking of the transparent material at or adjacent to the mouth of the bag during filling or other handling thereof, transparent materials of the kinds commonly used or available, such as "Cellophane" or material having the characteristics thereof, being more easily torn or broken than the paper from which the rest of the bag is made, especially when the upper end of the bag, including the transparent window-covering material, has a serrated edge or cut-off as shown, and being protected from tearing or breakage by the reinforcing strip. This reinforcing strip also provides convenient means for attaching the tie or closure means to the mouth of the bag and this tie, when fastened, will further strengthen the closed mouth of the bag and will prevent opening or breakage under the force of the contents of the bag during handling thereof.

While I have described the invention as applied to a bag, it is to be understood that the term "bag" is used in its broadest sense and is intended to include other similar or bag-like containers to which, it is obvious, the invention may be applied.

I claim as my invention:

1. A bag comprising a body portion composed of paper and having a window open-

ing in a wall thereof and portions of said wall at opposite sides of said opening extending longitudinally to the mouth of the bag, a strip of transparent material having the characteristics of "Cellophane" extending across said window opening and secured to said longitudinally extending portions of said wall, said transparent material having a serrated edge at the mouth of the bag, and a reinforcing strip for said transparent material extending across said window opening adjacent to the mouth of the bag and secured to said transparent material and to said portions of the bag wall at opposite sides of the window opening.

15 2. A bag comprising a body portion having a window opening in a wall thereof extending to the mouth of the bag, a strip of transparent material having the characteristics of "Cellophane" extending across said opening and secured to portions of said bag wall at the opposite sides of said opening, said transparent material having a serrated edge at the mouth of the bag, and a reinforcing strip for said transparent material extending across said window opening adjacent to the mouth of the bag and secured to said transparent material and the portions of the bag wall at opposite sides of the window opening and having a tie attached thereto for holding the bag mouth in closed condition.
